ELECTRICAL CONTROL PANEL

William D. Thomas, Ponca City, Okla., assignor to Continental Oil Company, Ponca City, Okla., a corporation of Delaware

Filed July 25, 1963, Ser. No. 75,970

Term of patent 14 years

(Cl. D26—13)

FIG. 1

FIG. 1 is a front elevational view of an electrical control panel, showing my new design; and

FIG. 2 is a slightly enlarged front perspective view.

The dominant feature of my design resides in the portion shown in full lines and a broken line showing of a cabinet and fenestrated portions of the front thereof is for illustrative purposes only.

I claim:

The ornamental design for an electrical control panel, substantially as shown and described.
